OSCILLATOR TUBE

John J. Rogan, Brooklyn, N. Y., assignor to Hy-grade Sylvania Corporation, Salem, Mass., a corporation of Massachusetts

Application September 23, 1933, Serial No. 690,665

2 Claims. (Cl. 250—27.5)

This invention relates to radio tubes and with particularity to tubes for generating carrier oscillations.

An object of the invention is to provide a novel form of tube for oscillation generation, detection or amplification.

One of the principal features of the invention relates to a tube employing a thermionic cathode and an electron-emitting anode.

Another feature relates to a novel form of radio tube possessing negative resistance characteristics.

A further feature relates to a radio tube for generating high frequency oscillations wherein the anode itself serves as a circuit inductance.

A still further feature relates to a tube suitable for use in generating waves of very short wave length.

Other features and advantages not specifically enumerated will be apparent after a consideration of the following detailed description and the appended claims.

Referring to the drawing, Fig. 1 is a schematic circuit diagram showing an oscillation system employing features of the invention;

Fig. 2 represents a modification of the system of Fig. 1;

Fig. 3 represents a further modification of the system of Fig. 1; and

Fig. 4 represents a structure of tube that may be employed in the system of Fig. 3.

Referring more particularly to Fig. 1, the numeral 1 indicates an enclosing envelope of glass or other similar material which is preferably evacuated to the point where ionization does not occur during the normal use of the tube. Suitably mounted within the envelope 1 is an electron emitting cathode 2 of any suitable type such as a filamentary cathode, an indirectly heated cathode or the like. Cooperating with the cathode 2 is an anode 3 of any suitable material, preferably of a synthetic graphite prepared in the manner disclosed in Patent No. 1,981,821. Mounted between the cathode 2 and the anode 3 is a control grid 4 of any well-known foraminous structure. Mounted outside the anode 3 is an auxiliary output electrode 5 which may be of either foraminous or plate-like material. The electrodes 2, 3, 4 and 5 may be of any desired shape such as ordinarily employed in the manufacture of radio tubes or the like. For example, the cathode 2 may be centrally located with respect to the grid 4, which may take the form of a helically wound wire or a perforated cylinder of metal. Similarly, the anode 3 may be in the form of a

cylindrical body surrounding the grid 4, and likewise the electrode 5 may be in the form of a cylinder surrounding the anode 3.

Any suitable type of input circuit may be employed such as schematically represented in the drawing by the transformer 6, which has its secondary connected across the grid 4 and the cathode 2, it being understood that if desired, a suitable biasing potential (not shown) may be inserted in the input circuit to bias the grid 4 with respect to the cathode 2. The output of the system includes a tuned oscillation circuit comprising the primary 7 of an output transformer which is shunted by a tuning condenser 8 in the manner well known in the radio art. The tuned oscillation circuit has one terminal connected to the anode 3 and the other terminal connected to the cathode 2 in series with a suitable source of anode potential 9, as indicated. The auxiliary output electrode 5 is also connected to the cathode 2 through a suitable source of potential 10, as indicated. Preferably, the electrode 5 is maintained at a higher potential than the anode 3 for purposes about to be described. Preferably also, the sources 9 and 10 are shunted by condensers 11, 12 to by-pass the generated oscillations there-around. As indicated by the numeral 13, the anode 3 is provided on its outer surface with a coating of electron-emissive material or materials, of any well-known composition. The tube is preferably designed so that during its normal operation there is sufficient emission from the cathode 2 and at sufficient velocity to raise the anode 3 by electron bombardment to a temperature at which the coating 13 emits the desired quantity of electrons. Heretofore, in the art it has been the usual practice, particularly in the case of transmitter tubes, to maintain the anode 3 as cool as possible, various expedients having been arranged for this purpose such as radiators, water cooling systems, or the like. The present invention, however, contemplates the utilization of the heat of the anode to render the latter emissive preferably as a primary emitter, and in order to render the tube more stable even with the anode operating at high temperature, this anode should preferably be of a material which is substantially entirely free from occluded or entrapped gases, either on its surface or on its interior. A synthetic graphite anode prepared in accordance with the disclosure of Patent No. 1,981,821, meets these requirements, and furthermore such an anode has the capacity of operation at even red heat without the liberation of gases within the envelope. While the anode 3 may be raised to emitting tem-

perature in any known manner, it is preferred, in accordance with this invention, to take advantage of the electron bombardment from the cathode 2. Consequently, sufficient potential should 5 be impressed upon the anode 3 to cause the electrons emitted from the cathode 2 to bombard the said anode 3 with sufficient velocity in order to raise the temperature of said anode to the required degree. If desired, an additional electron 10 accelerating electrode (not shown) may be interposed between the grid 4 and the anode 3. When the tube is operating with the anode 3 at the emitting temperature, the potential of the auxiliary electrode 5 is preferably adjusted so as to 15 impart to the output circuit a negative resistance characteristic. This condition can be attained since electrons arriving at the anode 3 from the cathode 2 tend to be neutralized by the primary electrons emitted from the anode 3 to 20 the auxiliary electrode 5 which, as above stated, is preferably at a higher potential than the anode 3. By a suitable adjustment of the relative potential of the electrodes 3 and 5 with respect to the cathode 2, a condition may be attained 25 wherein an increase of potential on anode 3 will result in a reduction in current in the output circuit, and vice versa. This negative resistance between the electrodes 3 and 5 may be designed with respect to the electrical constants of the 30 tuned oscillation circuit so as to result in the production of sustained oscillations in this latter circuit. These oscillations may, therefore, be impressed on a suitable radiating system such as the antenna 14 or the like.

35 It will be understood, of course, that the system of Fig. 1, while primarily designed for the production of sustained oscillations, by utilizing the primary electron emissions from the electrode 3, is also suitable for amplification or detection, 40 by choosing the proper bias of the control grid 4 with respect to the cathode 2. Furthermore, the system of Fig. 1 may be used as a combined oscillator-modulator by properly biasing the grid 4 and impressing the signals to be transmitted 45 through the transformer 6, resulting in the production in the output circuit of sustained oscillations which are modulated in accordance with the impressed signals.

50 The above described system is therefore capable of generating sustained oscillations without requiring any so-called feed-back between the output circuit and the input circuit, since the oscillatory condition is controlled entirely by the negative resistance characteristic obtainable by 55 the primary electron emission from anode 3 to the auxiliary electrode 5. In order to prevent any undesired feed-back between the output and input circuits, suitable neutralizing circuits well known in the art may be employed, or, if desired, 60 a so-called shield or screen grid may be interposed between the anode 3 and the control grid 4, which shield grid may be maintained at a lower potential than the anode 3.

65 Referring to Fig. 2, there is shown a system similar in general to Fig. 1, wherein both the inner and outer faces of the anode 3 are provided with emissive coatings. In this embodiment, the auxiliary electrode 5 completely surrounds the anode 3, both as regards the interior as well as 70 the exterior surfaces of the said anode, so as to utilize the primary emission from both surfaces of the anode. Here again the tube 1 is preferably designed so that during its normal operation as an oscillator, the anode is at an emitting 75 temperature, and advantage is taken of the nor-

mal bombardment of the anode from the cathode to produce primary emission from the said anode to the auxiliary electrode 5. By suitable adjustment of the relative potentials of the anodes 3 and 5 with respect to the cathode 2, the output circuit may be given any desired positive or negative characteristic and therefore the system of Fig. 2, like that of Fig. 1, may be used for oscillation, amplification, detection or modulation.

Referring to Fig. 3, there is shown a modification of the system of Figs. 1 and 2, wherein the main output anode is in the form of a coil 15 having the turns thereof freely spaced from each other so as to form in itself an electrical inductance. The auxiliary electrode 5, instead of being positioned exteriorly of the anode 15, is positioned between the control grid 4 and said anode 15. As indicated in Fig. 3, the electrode 5 is maintained at a higher potential than the anode 15 so that electrons, whether primary or secondary, from the anode 15, are attracted by the auxiliary electrode 5. If the tube 1 is to utilize only the secondary emission from the anode, then this anode may consist of bare wire such as molybdenum or the like, and the tube may be designed so that the said anode operates at less than the primary emission temperature. Due to the acceleration of the electrons from the cathode 2, these electrons pass through the openings in the electrode 5 and, striking the anode 15, result in the emission of secondary electrons from said anode. By properly proportioning the potentials and spacings of the electrodes 5 and 15, the output circuit comprising the inductance anode 15 and the condenser 16 may be given a negative resistance characteristic, and oscillations may therefore be produced in the said output circuit. Since the inductance anode 15 is included serially in the output circuit, the oscillatory currents therefore pass through the turns of the said inductance anode, and advantage may be taken of this current to render the anode 15 effective as a primary emitter, in which event the said anode 15 is preferably coated with electron emissive material or materials.

Referring to Fig. 4, there is shown a form of tube that may be used in the system of Fig. 3. In this figure the tube envelope is indicated by the line, and sealed to said envelope in the usual manner is a press 17 into which are sealed the various electrode support and lead-in wires. While Fig. 4 shows an indirectly heated cathode 2, it will be understood that any other type of cathode may be employed. The lead-in wires for the cathode heater filament are designated by the numerals 18, 19. Surrounding the cathode 2 is a grid 4 in the form of a helically wound wire having the turns thereof attached to support wires 20, 21. Surrounding the grid 4 is the foraminous electrode 5 of woven wire, mesh fabric, etc., although any other foraminous structure may be employed. This electrode 5 is provided with appropriate support wires 22, 23. Surrounding the electrode 5 is the coiled anode 15 having the turns thereof freely spaced from one another so as to provide an electrical inductance. The uppermost turn of the anode is connected to a support and lead-in wire 24, while the lowermost turn of the anode is connected to the lead-in wire 25. Thus the output current is enabled to flow serially through the individual turns of the anode inductance 15 for purposes described above in connection with Fig. 3. If desired, the anode 15 may be coated with electron-emissive material.

If desired, the grid electrode 4 may likewise

be wound with its turns freely spaced so as to provide an input inductance, and preferably, the circuit connections are such that the feed-back inductance effect of the anode 15 is in degenerative relation with respect to the inductance effect of the grid 4, so as to neutralize or prevent regenerative feed-back from the output to the input circuits.

5 While specific embodiments have been described herein, it will be understood that the invention is not limited thereto, but is capable of use in any tube for the production of oscillations by utilizing primary emission from the main or output anode.

10 15 Various changes and modifications may therefore be made without departing from the spirit and scope of the invention.

What I claim is:

1. An oscillator tube comprising an evacuated envelope, a cathode for emitting primary elec-

trons, an anode for receiving the electrons from said cathode, a control electrode between said cathode and said anode, said control electrode controlling the number of primary electrons from said cathode reaching said anode, said anode 5 having a coating of electron-emissive material on the side of said anode facing said control grid and being the output anode of the tube.

2. An oscillator tube comprising an evacuated envelope, an electron emitting cathode, an anode for said cathode, said anode having a coating of electron-emissive material thereon to act as a primary emitter under bombardment of the electrons from said cathode, and another electrode to act as an anode to the first-mentioned anode 15 and having portions disposed on opposite sides of said first-mentioned anode, said first-mentioned anode having said coating of electron-emissive material on both sides thereof.
